Design No. 16,735, dated June 15, 1886.

D 16735

UNITED STATES PATENT OFFICE.

CALEB M. CURREY, OF BAY CITY, MICHIGAN.

DESIGN FOR A CASE FOR SEWING-MACHINE FIXTURES.

SPECIFICATION forming part of Design No. 16,735, dated June 15, 1886.

Application filed March 9, 1886. Serial No. 194,664. Term of patent 14 years.

To all whom it may concern:

Be it known that I, CALEB M. CURREY, a citizen of the United States, residing at Bay City, in the county of Bay and State of Michigan, have invented a new and useful Design 5 for a Case for Sewing-Machine Fixtures; and I do hereby declare the following to be a full, clear, and exact description of the same, reference being had to the accompanying photograph, making part of this specification.

This invention consists in a design for a case for sewing-machine fixtures with two openings, one a round door in the end, as indicated by dark line. The other is indicated 15 by ornamented door in front of case.

The leading features of my design are an annular box of a flat configuration having an ornamentation which consists in a band with V-shaped scallops projecting over the periphery, a central annular panel representing a 20 door, and an irregular side panel, as illustrated in the photograph.

In the illustration, A represents the case; B, the central annular door-panel; C, the irregular side panel, the same having foliated leaf ornamentation and curved and straight geometric lines, as shown. D is the band, having V-shaped scallops projecting over the periphery. E indicates the perimeter of the door-panel, on which is the circular ornamental panel B.

I claim—

The design for a case for sewing-machine fixtures, the same consisting of an annular box of a flat configuration having an irregular 35 panel, C, on its periphery, a central door-panel, B, representing foliated leaves and curved and straight geometric lines, and a band having V-shaped scallops projecting over the periphery, as shown and described.

CALEB M. CURREY.
